Specification for Design.

Patented Mar. 9, 1920.

Application filed March 15, 1919. Serial No. 282,987. Term of patent 7 years.

To all whom it may concern:

Be it known that I, EVERETT H. BICKLEY, a citizen of the United States, and a resident of Philadelphia, county of Philadelphia, and State of Pennsylvania, have invented a certain new, original, and ornamental Design for Power-Pulleys, as shown in the accompanying drawings, in which—

Figure 1 is a front elevation of a power-pulley embodying the new design; Fig. 2 is a side elevation of the same; and Fig. 3 is a rear elevation of the same.

I claim:

The ornamental design for a power-pulley substantially as shown.

In witness whereof, I have hereunto set my hand this 13th day of March, A. D. 1919.

EVERETT H. BICKLEY.
